UNITED STATES PATENT OFFICE

LUIGI PEREGO, OF MILAN, ITALY
FUSE FOR BOMBS AND THE LIKE

Application filed January 24, 1930, Serial No. 423,142, and in Italy November 16, 1929.

The present invention relates to a fuse adapted to ensure the explosion as the result of percussion of any explosive device such as bombs, projectiles, torpedoes, explosive shells. 5 The fuse is characterized by arrangements which ensure the disassembly of the percussion mechanism under the action of a shock which may not have caused explosion, so as to render impossible the explosion of the device 10 under the action of any other shock or successive handling, so that the apparatus becomes completely harmless if it has not been exploded by the effect of the first shock.

The improved fuse is characterized essentially by having the two movable parts of its 15 percussion exploding mechanism held apart by means of a spring, these parts being mounted on two pieces which are respectively engaged in their active position in two recesses formed in the body of the explosive apparatus, one of the pieces and one of the 20 recesses being shaped so as to ensure the disengagement of the parts from the recesses under the action of any shock. The fuse is 25 further characterized by other supplementary structural arrangements relating to mounting and safety devices which are described in detail below.

The fuse forming the subject of the present invention is supposed in the following 30 description to be applied to a bomb suitable for throwing by hand or by a bomb throwing device. It will be evident that it may be applied in an analogous way by varying only 35 the subordinate arrangements, to any other suitable similar explosive.

The accompanying drawings illustrate by way of example and diagrammatically different ways of carrying the invention into practice.

Figs. 1, 2 and 3 illustrate respectively two side views partly in section and a transverse view of one construction.

Fig. 4 is a longitudinal section of another 45 construction.

Figs. 5 and 6 illustrate longitudinal and transverse views of a third construction.

Fig. 7 illustrates on a larger scale a priming arrangement in preferred construction. 50 Fig. 8 is a longitudinal section of a bomb

for throwing to which is applied the arrangement shown in Fig. 7.

In the construction illustrated in Figs. 1, 2 and 3, the body 1 of the bomb is cylindrical and in the neighborhood of its median plane 55 is provided with a hollow 2 in which is placed the priming mechanism. The said mechanism consists as usual of the two parts 4 and 4' (see Figs. 1 and 4), which are termed the "percussion masses". They are mounted on two conical pieces one of which carries the 60 striker and the other the priming. The said parts are kept apart by a spring 5 which normally is in the position of rest, the conical backs of the two carrying pieces being in engagement with the two recesses or cups 6, 6' which are solid with the body of the bomb and have an elliptical form, their edges being disposed in planes which are oblique with regard to the axes of the conical surfaces. 65

The part 4' is bored throughout its length by a hole allowing the spark to pass to the detonator and secondly to the explosive enclosed in the body of the bomb. 70

Corresponding to the hollow 2 is a plug 7 75 of suitable shape to adapt it to complete and lie flush with the outer cylindrical surface of the bomb. To this plug is rigidly fixed a fork 8 which is adapted to introduce itself, when the plug is in position, between the bodies 4 and 4', to keep them safely apart until the moment when the bomb is discharged. Any convenient means may be used to allow the plug to be drawn close against the body of the bomb (for example parts 10, 11 and 12 indicated in Fig. 4).

When the bomb is to be thrown the said locking means are removed, so that when it is thrown and during its trajectory the plug 7 with its fork 8 leaves the body of the bomb, so that at the moment of striking an object the percussion operates to explode the bomb. If for any reason the explosion does not take place the bomb presents no danger because the priming mechanism has become disassembled into two parts which are quite independent and it can no longer operate and the explosive device becomes harmless. Supposing that the shock strikes with one of its ends, the spring 5 is compressed and one of

the bodies 4 or 4', whichever is uppermost disengages itself from its corresponding cup 6 or 6'. Thanks to the inclination of the edge of the cup, the parts 4, 4' are freed by one of their extremities and turn upon themselves outwards and take up a position of equilibrium in which the axes of the conical pieces are perpendicular to the end planes of the cups. When the spring 5 expands the piece 10 which has left its cup cannot re-enter it because of the new position taken by the pieces 4 and 4'. The device is disassembled and the parts fall from the bomb by an opening provided in one of its sides.

15 The operation described cannot take place if the bomb strikes the ground on its side and particularly on the right side in Fig. 1.

In order to ensure that even in this case the object of the invention shall be attained 20 there are provided elastic leaves 9 for example of steel which embrace one part of the mechanism 4, 4'. At the moment of percussion, assuming that the bomb strikes an object with the side in question, the springs 9 react 25 so as to cause the parts 4, and 4' to leave their corresponding cups.

The construction illustrated in Fig. 4 operates in a manner which is analogous to that described above. It only differs from the latter in having the priming device disposed at the end of the bomb instead of in the middle.

In an analogous manner operates the construction illustrated in Figs. 5 and 6, but this differs from the first construction in that the explosion mechanism does not leave the body of the bomb but remains enclosed therein even after the bomb strikes, its parts being disassembled, however, in a chamber 13 provided in the apparatus.

In the preferred construction which is illustrated in Figs. 7 and 8 the priming device comprises two cylindrical parts 4, 4' shaped as cones and carrying respectively the striker 1 and the priming 2. These parts are kept apart by a reaction spring 3 and their conical ends engage in two supports 6, 6' provided with hollows or recesses the edges of which are suitably shaped.

In order that the ends of the percussive masses may be induced to leave their positions easily, at least one of the supports 6, 6' which in the construction illustrated have the form of hollow cylindrical cups, in which the conical ends engage, the edges of the said supports are formed on a curved line with the feature that they have a constant inclination with regard to the axis of the cup. Such a shape comprises the arcs of a helix suitably joined. A suitable inclination is about 22°. The axes of the cups may coincide as illustrated in Fig. 7 or they may be out of alignment with one another while remaining parallel. In that case the extremities of the cups have curvatures substantially parallel to one another

and inclined with regard to the axes of the cups 6, 6'. The said cups may be adjusted to the whole outer surface of the cones of the percussive masses or they may only touch at some points. They may have the form of a parallelopiped or of a cylinder with a directrix which is not circular, and may be hollow or solid. In some particular cases it is convenient to arrange these supports with their axes converging and to form the edges of the assembly with different curvatures, which will assure the bases 4, 4' leaving their supports only in a particular direction or even in opposite directions.

The constructive details of the invention 80 may be varied to meet practical requirements without departing from the spirit of the invention.

What I claim is:

1. A fuse for projectiles and the like, comprising a pair of movable members having outwardly extending ends, supports for engagement with said outwardly extending ends, and resilient means for normally urging said movable members into said supports, the engaging portions of said supports consisting of cylindrically-recessed portions having the engaging edges lying in a plane oblique to the axis of said recessed portions.

2. A fuse for projectiles and the like, comprising a pair of movable parts having projecting ends, supports for said movable parts, and resilient means for normally urging said movable parts into engagement with said supports, the engaging parts of said supports consisting of elliptically-recessed parts having the upper edges lying in a plane oblique to the axis of said elliptically-recessed parts.

3. A fuse for projectiles and the like, comprising a pair of movable parts, a pair of oppositely-disposed supports for said movable parts, and resilient means for normally urging said movable parts into engagement with said supports, the engaging portions of said supports consisting of cylindrically-recessed portions having the engaging edges lying in oblique planes to the axis of said recessed portions, the inclination of said edges being opposite, whereby upon shock said movable members are released from said supports at those points on the edges of said supports which are most distant from one another.

4. A fuse for projectiles and the like, comprising a pair of movable parts, a pair of oppositely-disposed supports for said movable parts, and resilient means for normally urging said movable parts into engagement with said supports, the engaging portions of said supports consisting of elliptically-recessed portions having the engaging edges lying in oblique planes to the axis of said recessed portions, the inclination of said edges being opposite, whereby upon shock said movable members are released from said supports at those points on the edges of said sup-

ports which are most distant from one another.

5. In a projectile having an opening in its wall, a fuse comprising a pair of movable members, supports for said movable members, and resilient means for normally urging said members into engagement with said supports, the engaging portions of said supports consisting of recessed portions having 10 their outer edges lying in planes oblique to the axis of said recessed portions, said edges being inclined in opposite directions, the most distantly separated portions being opposite said opening, so as to release said movable 15 members for passage through said opening upon shock.

6. In a projectile having an opening in its wall, a fuse comprising a pair of movable members, supports for said movable members, resilient means for normally urging said movable members into engagement with said supports, the engaging portions of said supports consisting of recessed parts having the outer edges of said parts lying in a plane 25 oblique to the axis of the supports, and the most distant portions of said edges positioned adjacent said opening, and elastic reaction members disposed opposite said opening to disassemble the parts upon lateral 30 shocks adjacent said elastic reaction members.

7. A fuse for projectiles and the like, comprising a pair of movable members, supports for said movable members, and resilient means for normally urging said movable 35 members into engagement with said supports, the engaging portions of said supports consisting of recessed portions, the outer edges of which are adapted to engage said movable members throughout the entire extent of said 40 edges.

8. A fuse for projectiles and the like, comprising a pair of movable members, supports having surfaces for said movable members, and resilient means for normally urging said movable members into engagement with said supporting surfaces, the engaging portions of said supporting surfaces consisting of recessed portions having their outer edges shaped in the form of the arcs of a helix.

50 9. A fuse for projectiles and the like, comprising a pair of movable members, supports for said movable members, and resilient means for normally urging said movable members into engagement with said supports, the engaging portions of said supports consisting of surfaces having their outer edges shaped so as to have at each portion thereof an inclination to the axis of the movable parts of substantially 22°.

60 In testimony whereof I affix my signature.
LUIGI PEREGO.
